UNITED STATES PATENT OFFICE

106,902

DESIGN FOR A FLOWER VASE HOLDER

Thomas S. Perez, Berkeley, Calif.

Application October 5, 1936, Serial No. 65,173

Term of patent 3½ years

To all whom it may concern:

Be it known that I, Thomas S. Perez, a citizen of the United States of America, residing at Berkeley, in the county of Alameda and State of California, have invented a new, original, and ornamental Design for a Flower Vase Holder, of which the following is a specification, reference being had to the accompanying drawing, forming a part thereof.

The figure is a perspective view of the flower vase holder showing my new design.

I claim:—

The ornamental design for a flower vase holder substantially as shown.

THOMAS S. PEREZ.
